[57] ABSTRACT

This disclosure is directed to a slide rule type device for determining the noise and reverberation which limits sonar performance. The device includes a base and cursor upon which related information has been placed. The cursor is operatively related with the data on the base such that associated information may be used for determining noise and reverberation for sonar equipment.

NOISE AND REVERBERATION SONAR RANGE COMPUTER

STATEMENT OF GOVERNMENT INTEREST

The invention described herein may be manufactured and used by or for the Government of the United States of America for governmental purposes without the payment of any royalties thereon or therefor.

BACKGROUND OF THE INVENTION

This invention relates to a hand operated computation device and more particularly to a computation device for determining and correcting for noise and reverberation which limits sonar operation.

SUMMARY OF THE INVENTION

This invention is directed to a hand operated computer device having a base upon which noise and reverberation data has been placed in combination with range in Kiloyards, thermal depth in feet, and frequency data have been placed. The cursor includes thereon noise and reverberation curves in combination with spaced parallel lines which are asymptotes to the curves. The cursor also includes spaced lines from which ranges may be obtained for desired probabilities of detection.

STATEMENT OF THE OBJECTS

It is therefore an object of the present invention to provide a hand operated computation device for computing ambient noise and reverberation which limits sonar performance.

Another object is to provide a simple efficient, inexpensive computation device for computing noise and reverberation which limits sonar performance.

Still another object is to provide a noise and reverberation computation device which may be used by unskilled as well as skilled personnel.

Other objects and advantages of the invention will become obvious to others upon reading the following description of the drawings.

BRIEF DESCRIPTION OF THE DRAWINGS

FIG. 1 illustrates a top view of the device; FIG. 2 illustrates the base with data thereon; and FIG. 3 illustrates a separate view of the cursor.

DESCRIPTION OF THE DRAWINGS

Now referring to the drawings there is shown by illustration a computation device for correcting the performance of a sonar in determining range. As shown, the device includes a base 10, upon which data has been placed. Above the base there is located a slidable cursor 11 which includes reference lines as well as frequency correction information.

The base may be formed of a solid material such as plastic, metal, wood or any other desired material and of rectangular shape. Across the length of the bottom, there are placed four linear scales 13-16 of numerical information graduated in accordance with data obtained by well known equations for well known sonar equipment. Two of the linear scales 13 and 15 are for noise and scales 14 and 16 are for reverberation. The letters of R1, N1, R2, and N2 refer to noise and reverberation, as limiting factors, and the numbers by the letters refer to a two-dimensional or a one-dimensional

transducer. The figures on the scales are formed by the following equations:

R1 - Reverberation for a one-dimensional transducer

$$R1 = 10 \log \frac{l}{t \cos^2 \theta} \left[\frac{l}{200} + \left(\frac{V ft \cos \theta}{2350} \right)^2 \right]$$

10 N1 - Noise for one-dimensional transducer

$$N1 = 10 \log \frac{P P_t}{(n+1)^3 \cos^2 \theta}$$

15 R2 - Reverberation for two-dimensional transducer

$$R2 = 10 \log \frac{Af}{t \cos^2 \theta} \left[\frac{l}{200} + \left(\frac{V ft \cos \theta}{2350} \right)^2 \right]$$

N2 - Noise for two-dimensional transducer

$$N2 = 10 \log \frac{PA^2 t}{(n+1)^3 \cos^2 \theta} \text{ or } -2V + 10 \log \frac{PA^2 t}{2 \cos^2 \theta}$$

where

P = Acoustic power

A = Transducer Area (cm)²

t = pulse length (milliseconds)

n = sea state, characterizing ambient noise

l = transducer length (cm)

θ = aspect angle from 0° to 90°

$\cos \theta = \cos \theta$ from 0° to 80°

= 0.173 from 80° to 90°

f = frequency

f_{n1}, f_{n2} = Optimum frequency for noise limited range

V = target speed (Knots)

V = speed of carrier (knots for airborne equipment)

40 If the directivity is D at a frequency f, then the area A may be taken from $10 \log A = 32.7 + D - 20 \log f$.

If the directivity is D at a frequency f, then the length may be from $10 \log l = 18.8 + D - 10 \log f$.

45 Immediately above the scales on the base, there is a logarithmic coordinate system tilted at a 45° angle with respect to the linear scales on the bottom portion of the base. The lines 17 of the logarithmic scale that extend upwardly and to the right indicate the thermal depth, d, values in feet (20-400) which are shown along the bottom near the edge of the scales. The lines 18 extending upwardly to the left indicate range in Kiloyards, the values are shown along the upper left and right edges of the coordinate system.

50 55 Further, there is shown a plurality of parallel lines 21 extending from the thermal depth scale upwardly to a curved line 22. The curved line is used to determine the range of a target below the thermocline. The curve is such that the parallel lines extend from the edge of the curved line ends at the corresponding range. The curved line is determined by well known sonar formula which relates depth to range.

The two straight lines F_{n1} and F_{n2} serve to determine the optimum frequency for a noise limited range. The lines are determined for specific equipment and the lines relate depth to frequency.

The noise and reverberation scale information is related to the thermal depth in feet and range in Kiloyards by use of a cursor which is moveable along the

base. The cursor contains thereon three curves 26, 27, and 28 which extend from the upper left corner toward the bottom and right side. The curves are formed from data relating the noise and reverberation to the thermal depth in feet and the range in Kiloyards. The cursor includes a vertical line 31 that extends across all of the scalar lines. This line is used in determining the nominal range, that is, the range obtained with a 50% probability of detection. The short vertical lines 32-35 (10, 30, 70 and 90) on each side of the long line for each of the scalar lines serve to find the ranges obtained with the respective probabilities. The slope of the lines on the cursor are such that when the probability line selected is placed over the corresponding noise or reverberation scale, the point of interception of the thermal depth line with the corresponding curve will give the range. The range of operation will be with the smaller range, as determined for the noise and reverberation, corresponding to the conditions. The noise and reverberation may be determined by the above formulas depending on the equipment and the different parameters that affect the sonar signal.

Operation of the computation device for determining sonar range with equipment operating with the following parameters;

$$\begin{array}{ll} P = 32W & ; t = 120 \text{ milisec} \\ f = 20Kc & ; N = 4 \\ A = 420\text{cm}^2 & ; \text{Thermal depth - 150 feet} \end{array}$$

target speed = 3 Knots; $\theta = 60^\circ$ (target above the thermocline) is as follows:

Step 1:

Calculate characteristic figures N2 and R2 from the formulas previously given above for the above given conditions:

$$N2 = 73.4 \text{ db}$$

$$R2 = 29.2 \text{ db}$$

These values may also be obtained by use of a chart which shows a direct relationship between ships speed, target speed and the Figure of merit.

Step 2:

Slide the cursor 1 until the long probability mark 45 "50" (line 31) is set directly over 73.4 on scale 13 (N2).

Step 3:

Follow line $d = 150$ up to its intersection with curve 50 26 (N2). Read the value of Range r of this point which is found to be 4.2 Ky. This is the noise limited range r_N .

Step 4:

Move the cursor so that the "50" line is over 29.2 of 55 the R2 scale, follow line $d = 150$ to its intersection with curve 28 R1R2. Read the Range value r of this point which is 3.9 kyd. This is the reverberation limited range, r_R at optimum frequency.

Step 5:

Estimate the correction to r_N corresponding to the operational frequency. No such correction is required for reverberation limited range found by the computer.

Step 6:

Find the optimum frequency f_0 by following the line $r = r_N$ (4.2 ky) to its intersection with the line $fN2$ going

right and up from this point, read f_0 on the upper edge at 17 Kertz.

Step 7:

5 The range corresponding to an operating frequency f , r_f is smaller than the range at optimum frequency, r_N by a fraction b which is for a rough estimate; $b = 0.05 (k^2 - 1)$ when $K = f/f_0$ for $f < f_0$ and f_0/f for $f > f_0$.

10 If f deviates from f_0 by less than 20% the range correction is smaller than 2%.

15 For more precise information, form the ratio f/f_0 and read with this value as abscissa, the ordinate from curve R2(db) subtract this from N2 and read r for the reduced characteristic figure. This is the noise limited range r_f for a frequency f . In the example $f_0 = 20$, $f = 17$ for this abscissa C2 has the $f/f_0 = 1.18$ value of 0.6 db. The reduced characteristic figure is $73.4 - 0.6 = 72.8$; the noise limited range is 4.15 ky instead of 4.2 kyd.

EXAMPLE 2

With data as in example 1, but target below the thermocline, proceed as follows:

25

Step 1:

Set cursor at N2 = 73.4.

Step 2:

30 From the point 150 on d scale, follow a line to the left and up to its intersection with the curve 22 marked "target below thermocline". From this point follow the line $d = \text{constant}$ (62 in the example) up to the intersection with curve N2 giving $r_N = 3.3$ Kyds.

Step 3:

35 apply the correction for non-optimum frequency to r_N . Similarly, with the cursor set at R2 = 29.2 follow the line $d = 62$ to intersection with curve R1R2 giving $r_R = 2.4$ Kyd.

Note: In any given position of the cursor the ranges can be read for all depths for thermocline represented on the computer for "target above" as well as for "target below" the thermocline.

EXAMPLE 3:

45 Data as in Example 1, ranges to be determined for a probability other than 50%. To find the noise limited range for a probability of say 10% slide cursor to a position where the index line "10" belonging to scale N2 is set at 73.4 on scale N2 proceeding as before, one finds $r_N = 5.0$ ky for $d = 150$ ft. To find the reverberation limited range for a probability of 10%, slide cursor to a position where the indices "10" belonging to scale R2 is set at 29.2 on scale R2 proceeding as in paragraph 5 above, one finds $r_R = 6.4$ Kyd for $d = 150$ ft. The probability at other % values may be obtained by moving the cursor such that the desired value is over the determined value on the noise and reverberation scales as set forth above.

50 The curve 30 on the left of the device may be used for determining a correction factor which may be used to find the final operable range as set forth above.

55 Obviously many modifications and variations of the present invention are possible in the light of the above teachings. It is therefore to be understood that within the scope of the appended claims the invention may be practiced otherwise than as specifically described.

60 What is claimed and desired to be secured by Letters Patent of the United States is:

1. A device for determining noise and reverberation that limits sonar performance, which includes, a base, a plurality of rows of different scale values extending in parallel across the bottom of said base, said base including thereon a portion of a logarithmic scale extending across said base at 45° angle above said scale values, said logarithmic scale lines extending to the right and upwardly representing depth in feet, said depth values indicated along the bottom of said logarithmic scale, said logarithmic scale lines extending upwardly and to the left representing range values in kiloyards, said range values aligned along the sides of said logarithmic scale, a cursor positioned over said base for linear movement relative to said base, said cursor including thereon three curved lines and a plurality of vertical parallel lines, said vertical lines relating said curved lines to depth and range in accordance with probability of detection,

5

10

15

20

25

said vertical lines aligning with different rows of said plurality of rows of different scale values on said base, and a single probability line on said cursor that extends across the total number of rows of said plurality of rows of different scale values on said base. 2. A device as claimed in claim 1; wherein, said base includes two parallel lines extending across said logarithmic scale from the bottom edge to the top edge, optimum frequency values extending across the top of said logarithmic scale, and said pair parallel lines are related to said optimum frequency values noted on the base. 3. A device as claimed in claim 2; which includes, a curve extending across said logarithmic scale for determining range and reverberation of a sonar for a target below the thermocline. 4. A device as claimed in claim 3; which includes, a correction scale in combination with said logarithmic scale for correcting the optimum frequency to an operating frequency.
